UNITED STATES PATENT OFFICE.

JOEL HAYDEN, JR., OF BOSTON, MASSACHUSETTS, ASSIGNOR, BY MESNE ASSIGNMENTS, TO HAYDEN MACHINERY COMPANY, A CORPORATION OF MAINE.

RING SPINNING AND TWISTING APPARATUS.

No. 814,783.

Specification of Letters Patent.

Patented March 13, 1906.

Application filed December 28, 1904. Serial No. 238,635.

To all whom it may concern:

Be it known that I, JOEL HAYDEN, Jr., a citizen of the United States, residing in Boston, in the county of Suffolk and State of Massachusetts, have invented certain new and useful Improvements in Ring Spinning and Twisting Apparatus, of which the following is a specification.

This invention relates to that class of ring spinning and twisting apparatus in which the ring is non-rotative—that is, while it may have some slight horizontal or approximately rotative movement such movement does not entitle it to be termed a "rotary" ring, as there is no continuous movement and of course no complete rotation. The ring belongs, therefore, to the class usually termed "stationary" rings.

This invention has for its principal object to prevent the wearing of the lower flange on the ring, such wear being commonly produced by the vibration of the ring and its direct contact with the supporting plate or holder, and to obviate the necessity for mutilating the ring in order to engage it by means of clips or similar devices extending from the supporting-plate by introducing between the spinning-ring and the supporting-plate an intermediate member which is adapted not only to be sprung or snapped over the lower flange of the ring, but to accommodate itself to rings of different sizes and to provide means whereby a suitable instrument, such as a knife-blade, can be used to separate the ring from the intermediate member by springing or prying it out of engagement therewith or to spread the intermediate ring for the purpose of inserting the spinning-ring.

The nature of the invention is fully described below and illustrated in the accompanying drawings, in which—

Figure 1 is a plan view of a spinning-ring, the supporting plate or holder, and my improved intermediate member assembled and in position on the ring-rail and embodying my invention. Fig. 2 is a similar view with the spinning-ring removed. Fig. 3 is a vertical section taken on line 3 3, Fig. 1. Fig. 4 is a vertical section taken on line 4 4, Fig. 1.

Similar letters of reference indicate corresponding parts.

The spinning-ring *a* is constructed in the

ordinary manner and provided with the upper and lower flanges *b* and *c*.

d represents the supporting plate or holder, 55 and *e* the ring-rail.

Intermediate of the supporting plate or holder and the spinning-ring is a curved or C-shaped spring member *g*, whose ends *g'* face each other, as shown in Fig. 2, but do not 60 quite meet, the said member constituting a split ring. This member is formed on its inner edge with a flat horizontal ledge *f*, upon which the spinning-ring is adapted to rest, and is provided with the upwardly and inwardly extending annular lip *h*, which is adapted to be sprung over the edge of the flange of the spinning-ring, and thereby retain said ring permanently in position. Moreover, this member, which is preferably thick 70 and heavy, is provided with radial passages *k*, into which the clips *m*, which are integral with and bent upward or inward from the plate *d*, are adapted to extend, thereby holding the intermediate member and supporting- 75 plate in engagement.

To assemble the parts, the clips *m* are sprung over the edges *l* into the passages *k*, and the spring member *g* is forced over the edge of one of the flanges of the spinning-ring, 80 said member yielding and having its ends *g'* forced apart to a greater or less extent, according to the size of the spinning-ring or its flange, and then overlapping and holding said flange by means of the lip *h*.

It is desirable that there should be some provision whereby the end of a thin instrument, such as a knife-blade, can be used to spread the intermediate member when the spinning-ring is to be inserted and to assist 90 in prying the spinning-ring out of engagement therewith. I have provided, therefore, vertical and horizontal recesses or notches *p* and *s*. The recess or notch *p* is formed vertically in the lip *h*, as shown in Figs. 1, 2, and 95 3, and extends practically through said lip horizontally down to about the level of the ledge *f*. When the spinning-ring is to be applied, a blade is inserted vertically in this recess and the flange of the ring pushed down 100 into position. The recess or notch *s* is formed horizontally in the body of the member *g*, as illustrated in Figs. 1, 2, and 4, and extends below the level of the ledge *f* and un-

der the ring. To pry the spinning-ring out of engagement, an instrument is inserted horizontally in this recess under the flange of the ring.

5 Having thus fully described my invention, what I claim, and desire to secure by Letters Patent, is—

1. In an apparatus of the character described, the spinning - ring, the supporting plate or holder, a permanent spring member of the shape of a split ring intermediate of the spinning-ring and the supporting plate or holder and rigid with the spinning-ring and resting wholly on the horizontal surface of the plate or holder, and means for connecting said plate or holder and intermediate spring member whereby said member is allowed to move horizontally on the surface of said plate or holder but prevented from continuous ro-
20 tative movement.

2. In an apparatus of the character de-
scribed, the spinning - ring, the supporting plate or holder, a permanent spring member of the shape of a split ring intermediate
25 of the spinning-ring and the supporting plate or holder and rigid with the spinning-ring and resting wholly on the horizontal surface of the plate or holder, and means for connecting said plate or holder and intermediate
30 spring member whereby said member is al-
lowed to move horizontally on the surface of said plate or holder and is in contact there-
with during the entire horizontal movement.

3. In an apparatus of the character de-
scribed, the spinning - ring, the supporting plate or holder having a flat horizontal upper surface, a permanent weighted spring member of the shape of a split ring interme-
35 diate of the spinning - ring and supporting
40 plate or holder and rigid with the spinning-
ring and resting on the horizontal surface of the plate or holder, and means for connecting said plate or holder and intermediate mem-
ber whereby said intermediate member is al-

lowed curved horizontal movement on lines 45 which are non-concentric with the periphery of the spinning-ring but prevented from con-
tinuous rotative movement.

4. In an apparatus of the character de-
scribed, the combination with the spinning-
ring and the supporting plate or holder, of a
member intermediate of the plate or holder
and the spinning - ring and adapted to be
spread or sprung over a flange of the ring,
said intermediate member being provided 55
with recesses or notches adapted to receive
an instrument whereby the ring may be as-
sisted into or out of engagement with said in-
termediate member.

5. In an apparatus of the character de-
scribed, the combination with the spinning-
ring and the supporting plate or holder, of a
member intermediate of the plate or holder
and the spinning - ring and adapted to be
spread or sprung over a flange of the ring, 60
said intermediate member being provided
with a substantially horizontal recess or notch
extending under the flange of the ring when
it is in engagement with said member for the
purpose set forth.

6. In an apparatus of the character de-
scribed, the combination with the spinning-
ring and the supporting plate or holder, of a
member intermediate of the plate or holder
and the spinning - ring and adapted to be
spread or sprung over a flange of the ring, 65
said intermediate member being provided
with a substantially vertical recess or notch ex-
tending down outside the flange of the ring
when it is in engagement with said member,
70 for the purpose set forth.

In testimony whereof I have signed my
name to this specification in the presence of
two subscribing witnesses.

JOEL HAYDEN, JR.
